UNITED STATES PATENT OFFICE

2,578,372

COMBINATION CRIB AND CRADLE

William Pope, New Orleans, La.

Application October 21, 1949, Serial No. 122,790

6 Claims. (Cl. 5—106)

1

The present invention relates to a combination crib and cradle and it consists in the combinations, constructions and arrangements of parts herein described and claimed.

Generally there is provided a combination crib and cradle which comprises a pair of rocker members having upwardly extending centrally disposed arms interconnected at their upper ends to form an axle upon which is suspended a crib. A pair of vertically movable legs is mounted upon each of the rocker members and each of the pairs of legs is provided with an upwardly extending shaft which is provided with an integrally formed inwardly extending abutment which is adapted to engage in a notch at the side of the crib to lock the same when the shaft is lowered. When the shaft is in upraised position the bottoms of the rockers are free to contact the floor and the device may be rocked back and forth in the manner of an ordinary cradle but with the exception that the crib, being suspended, will remain level with the floor at all times. When the shaft is in lowered position, the crib is locked with the upright members and the rollers are in contact with the floor. The device then forms a rigid structure which may be moved from place to place by means of the rollers. With slight alterations, the device may be utilized as a swing.

It is accordingly an object of the invention to provide a device of the character set forth which is simple in construction and operation and which is effective and efficient in use.

Another object of the invention is the provision of a combination baby crib and cradle.

Another object of the invention is the provision of a novel locking means whereby a crib may be locked with other apparatus forming a part of the invention to provide a rigid structure.

A further object of the invention is the provision, in a device of the character set forth, of novel retractable supporting rollers.

A further object of the invention is the provision, in a device of the character set forth, of novel supporting means for the swinging supports of a crib forming a part of the invention.

Other and further objects of the invention will become apparent from a reading of the following specification taken in conjunction with the drawing, in which:

Figure 1 is a side elevational view of an embodiment of the invention,

Figure 2 is an end elevational view thereof,

Figure 3 is a sectional view taken along line 3—3 of Figure 2,

Figure 4 is a sectional view taken along line 4—4 of Figure 1, and

Figure 5 is an enlarged fragmentary perspective view illustrating certain details of construction.

Referring more particularly to the drawing,

2

there is shown therein a pair of spaced parallel rockers 10 each provided with a centrally disposed upwardly extending support 11 having a longitudinal opening 12 therein.

5 An axle 13 is provided with integrally formed downwardly extending legs 14 which are embedded in the upper ends of the support members 11, as indicated at 15.

The lower ends of the rockers 10 are interconnected by means of a transversely extending cross bar 16 and an abutment 17 is disposed in spaced relation above the bar 16 on the inner side of each of the rockers 10.

10 Mounted for vertical reciprocal movement on the inner face of each of the rockers 10 between the bar 16 and the abutment 17 is an arcuate roller support 19 having its concave face presented toward the floor and provided, in each case, with a roller 20 at each of its outer ends.

15 A block 21 is mounted in the opening 12 in each of the members 11 adjacent the upper end of said opening and a shaft 22 is slidably mounted in the block and extends vertically in the opening 12 and inwardly, as indicated at 23 and thence downwardly through the abutment 17 and is fastened within the support 11 by means of a set screw 24. A set screw 25 is provided in the block 21 whereby to lock the shaft 22 in either its upward or its lowered positions and the upper end of the shaft 22 is provided with an inwardly extending integrally formed latch member 26 which is adapted to engage in a notch 27 formed in the side of a crib 28. The crib 28 is provided with a pair of eyes 29 in either side thereof and each is adapted to receive one end of a supporting cable 30 which is looped, as indicated at 31, through a ring 32 which is, in turn, connected with a ring 33 which surrounds the axle 13.

20 In operation, it will be apparent that when the shaft 22 is moved upwardly that the support member 19 will likewise be moved upwardly and that the rollers 20 will be freed from contact with the floor whereupon the rockers 10 will be free to rock and that at the same time the member 26 will be free from its notch 27 whereby the crib 28 may be free to swing upon the axle 13 and that as the device is rocked upon the rockers the crib 28 will, through gravity, maintain a substantially parallel position with the floor at all times.

25 When it is desired to utilize the device as an ordinary crib, however, the shafts 22 are moved downwardly whereupon the members 26 will engage in the notches 27 and the rollers 20 will come into contact with the floor and the rockers 10 will be raised from the floor. The device in such condition will be rigid and may be moved from place to place upon the rollers 20 in much the same manner as the ordinary crib. It will

also be apparent that the shaft 22 may be locked in either its upward position or in its downward position, as above set forth, by means of the set screws 25.

While but one form of the invention has been shown and described herein, it will be readily apparent to those skilled in the art that many minor modifications may be made without departing from the spirit of the invention or the scope of the appended claims.

What is claimed is:

1. A device of the character described comprising a pair of spaced parallel rockers, an upright member centrally connected with each rocker, a crib, means for swingably suspending said crib upon said upright members, a pair of rollers carried by each of the upright members, means for raising and lowering said rollers above and below the bottoms of said rockers and means associated with said raising and lowering means for locking the crib to said upright members.

2. A device of the character described comprising a pair of spaced parallel rockers, an upright member centrally connected with each rocker, a crib, means for swingably suspending said crib upon said upright members, a pair of rollers carried by each of the upright members, means for raising and lowering said rollers above and below the bottoms of said rockers, and means associated with said raising and lowering means for locking the crib to said upright members and means for locking said raising and lowering means in selected positions.

3. A device of the character described comprising a pair of spaced parallel rockers, an upright member centrally connected with each rocker, a crib, means for swingably suspending said crib upon said upright members, a roller support vertically movable at the inner side of each of the rockers, a roller mounted at either end of each of said roller supports, means for raising and lowering said rollers above and below the bottoms of said rockers and means associated with said raising and lowering means for locking the crib to said upright members.

4. A device of the character described comprising a pair of spaced parallel rockers, an upright member centrally connected with each rocker, a crib, means for swingably suspending said crib upon said upright members, a roller support vertically movable at the inner side of each of the rockers, a roller mounted at either end of each of said roller supports, means for raising and lowering said rollers above and below the bottoms of said rockers and means associated with said raising and lowering means for locking the crib to said upright members, said means for raising and lowering the rollers including a vertically movable shaft in each of the upright members and each affixed at its lower end to a roller support.

5. A device of the character described comprising a pair of spaced parallel rockers, an upright member centrally connected with each rocker, a crib, means for swingably suspending said crib upon said upright members, a roller support vertically movable at the inner side of each of the rockers, a roller mounted at either end of each of said roller supports, means for raising and lowering said rollers above and below the bottoms of said rockers and means associated with said raising and lowering means for locking the crib to said upright members, said means for raising and lowering the rollers including a vertically movable shaft in each of the upright members and each affixed at its lower end to a roller support and said means for locking the crib to the upright members including a notched block on either side of said crib and an inwardly extending portion formed at the upper end of each shaft and adapted to engage said notch when the shaft is lowered.

25 6. A device of the character described comprising a pair of spaced parallel rockers, an upright member centrally connected with each rocker, a crib, means for swingably suspending said crib upon said upright members, a roller support vertically movable at the inner side of each of the rockers, a roller mounted at either end of each of said roller supports, means for raising and lowering said rollers above and below the bottoms of said rockers and means associated with said raising and lowering means for locking the crib to said upright members, said means for raising and lowering the rollers including a vertically movable shaft in each of the upright members and each affixed at its lower end to a roller support, said means for locking the crib to the upright members including a notched block on either side of said crib and an inwardly extending portion formed at the upper end of each shaft and adapted to engage said notch when the shaft is lowered and said means for locking said raising and lowering means comprising a block carried by each upright member and having an opening 30 for the passage therethrough of its associated shaft and a set screw for each of said blocks adapted to bear against its shaft.
